UNITED STATES PATENT OFFICE.

CLARENCE M. CREWS, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed November 13, 1923. Serial No. 674,430.

This invention relates to devices used in typewriting machines, for holding stencil-cards and the like to be typed upon.

The backing of the card-holder, formed of celluloid or like material, is attached by its top edge to the platen, and extends in front thereof to overlie the printing field. The lower portion of said celluloid sheet is folded upwardly at the front to form a pocket to hold the stencil-card. The card-holder is readily bendable around the platen, and is held thereto by the usual downwardly-extending front guiding fingers, which have rolls mounted thereon.

One of the main objects of the present invention is to provide simple and efficient means for connecting the card-holder to be line-spaced with the platen.

The top of the celluloid backing-sheet may be attached to the platen by means of a bar suitably fastened to the backing, and extending the length of the platen; the ends of said bar being bent to form forked arms to bestride flattened portions of the hubs of the usual platen ends. Claws at the free ends of the forked arms catch over the platen ends. The claws are releasable from the platen ends so that the card-holder may be lifted from the platen.

Another object of the invention is the provision of means for preventing a bulging or bending out of the card-holder at the printing point, consisting of a finger mounted on the rod which supports the usual downwardly-extending paper-guiding fingers, so that clear-cut type-impressions may be made on the stencil-card.

The device may be readily attached as a unit to the typewriting machine, and may be readily removed therefrom when it is desired to use the typewriter for typing upon ordinary work-sheets.

Other features and advantages will hereinafter appear.

In the accompanying drawings,

Figure 1 is a view, in front elevation, of a revoluble platen of a typewriting machine embodying the present invention.

Figure 2 is a view in side elevation, partly in section, of that shown in Figure 1.

Figure 3 is a sectional view, taken on the line 3—3 in Figure 1, showing the auxiliary guide-finger at the rear of the stencil-card.

Figure 4 is a diagrammatic sectional view, in side elevation, showing the card-holder in

a position raised from that shown in Figure 2.

In the drawings, a platen 10 may be mounted on a platen-axle 11 by means of the usual end plates 12 having hubs 13. The axle 11 may be journaled in the platen-carriage side plates 14. Guides 15, slidably and swingably mounted on a rod 16, may be provided, one on each end of the platen 10, in the well-known manner. Each guide 15 may consist of the usual downwardly-extending paper-finger 17 having thereon a roll 18 mounted to ride on the platen 10. In Figure 1, shown in dotted lines, 19 and 20 locate the wing-scale and the type-bar segment respectively with reference to the platen 10. In Figure 2, type-bar 21 is also shown in dotted lines in a backwardly-swung position between upstanding members of the type-bar guide 22, which locates the printing position 75 on the platen 10, indicated in Figure 1 by the letter "X".

A stencil-card holder 23 comprises a backing portion or impression sheet 24 forming with a stencil-card holding frame 25 80 a pocket 26, into which a stencil-card 26^a may easily be inserted. The bottom of the pocket 26 and the right-hand edge-gage 27 may be used to position and properly align the stencil-card 26^a for typing. The backing portion 24 is guided and held against the platen 10 by the guides 15, which press on lateral extensions 24^a of backing 24, in the usual manner, as shown in Figures 1 and 2. The wing-scale 19 aids in holding the 90 card-holding frame 25 and the stencil-card 26^a to the platen 10 at the printing line, and the type-bar segment 20 may act as a stop to limit the downward position of the card-holder 23.

A connecting strip member 28 may be provided to detachably mount the stencil-card holder 23 to move with the platen 10. The member 28 comprises a springy, metal strip 29 extending the length of the platen 10, to which the supporting backing portion 24 of the stencil-card holder 23 is fastened in any suitable manner, as by means of rivets 30. Each end of the strip 29 may be bent down and shaped to form forked arms 31, 100 which bestride flattened faces 32 on the hubs 13. The faces 32, straddled by the arms 31, form a mechanical attachment for connecting the member 28 to the platen 10, which requires the card-holder 23 to be line-spaced 110

with the platen 10. The arms 31 at their free ends have claws 33 to catch over the rims of the platen end plates 12, for locking the attaching means to the platen 10.

5 Relatively stiff releasing pieces 34, formed to correspond in shape with the forked arms 31, are fastened to the arms 31 at their lower extremities in any convenient manner, as by soldering. The releasing pieces 34 extend

10 upwardly and outwardly from their fastenings on arms 31, and, when it is desired to detach the card-holder 23 from the platen 10, a slight inward pressure on the pieces 34 toward the ends of the platen 10 acts to release the claws 33 from the platen end plates 12, so that the card-holder 23 may be lifted from the platen 10.

15 A downwardly-extending auxiliary guide-finger 35 may be swingably and slidably mounted on the rod 16 for engaging the backing portion 24 behind the stencil-card 26 adjacent the printing point to keep the backing portion 24 against the platen 10. With the card-holder 23 in the position shown in Figures 1 and 2, the stencil-card 20 will positively be carried with the platen 10 when the latter is given a line-space movement in the usual manner.

25 Variations may be resorted to within the scope of the invention, and portions of the improvements may be used without others.

30 Having thus described my invention, I claim:

35 1. In a typewriting machine, a platen, a card-holder mounted on the platen, including an impression sheet or backing portion forming part of a receiving pocket to hold a stiff work-piece in flat condition against the platen for typing, and releasable means for locking the card-holder to the platen to assure line-space movement therewith.

40 2. In a typewriting machine, a platen, a card-holder mounted on the platen, including an impression sheet or backing portion forming part of a receiving pocket to hold a stiff work-piece in flat condition against the platen for typing, releasable means for locking the card-holder to the platen to assure line-space movement therewith, said sheet having lateral extensions, and means associated with the platen for pressing said lateral extensions against the platen.

45 3. In a typewriting machine, a platen, a card-holder mounted on the platen for line-space movement therewith, including a flexible impression sheet or backing portion forming part of a receiving pocket for a work-piece, and means associated with the platen at the rear of the work-piece for preventing the bulging and bending of the impression sheet adjacent the printing point.

50 4. In a typewriting machine, a platen, a card-holder mounted on the platen, includ-

ing a flexible impression sheet or backing portion forming part of a receiving pocket for a work-piece, means associated with the platen at the rear of the work-piece for preventing the bulging and bending of the impression sheet adjacent the printing point, and means for locking the card-holder to the platen to assure line-space movement therewith.

55 5. In a typewriting machine, a platen, a platen-frame, a card-holder mounted on the platen, including an impression sheet or backing portion forming part of a receiving pocket to hold a stiff work-piece in flat condition against the platen for typing, releasable means for locking the card-holder to the platen to assure line-space movement therewith, said sheet having lateral extensions, means moving with the platen for pressing said lateral extensions against the platen, and means mounted on the platen-frame at the rear of the work-piece, for holding the impression sheet adjacent the printing point against the platen.

60 6. The combination with a revoluble platen, of a stencil-card holder, including a backing portion or impression sheet for a work-piece, and also including a strip extending along the platen for holding the upper edge of said backing portion to the platen, and depending ends on the strip releasably locked to the ends of the platen, to assure line-space movement of the card-holder therewith.

65 7. In a typewriting machine, a revoluble platen, a platen-frame, a card-holder having one end thereof fastened on the platen to assure line-space movement therewith, said card-holder including a flexible backing portion forming part of a receiving pocket for a work-piece, and an adjustable guide-finger, mounted upon said platen-frame and extending into the pocket at the rear of the work-piece for holding the backing portion adjacent the printing point against the platen.

70 8. The combination with a revoluble platen, of a stencil-card holder including a backing portion or impression sheet for a stencil-card, means for attaching said card-holder to the platen, with one end of the sheet free, and for holding the body of the sheet against the platen, and means for releasably locking said card-holder to the platen to assure line-space movement therewith.

75 9. The combination with a revoluble platen, of a stencil-card holder including a backing portion or impression sheet for a stencil-card, means for attaching said card-holder to the platen, with one end of said sheet free, and for holding the body of the sheet against the platen, means for locking said card-holder to the platen to assure

line-space movement therewith, said sheet having lateral extensions, and means associated with the platen for pressing said lateral extensions against the platen.

5 10. The combination with a revoluble platen, of a stencil-card holder including a backing portion or impression sheet for a stencil-card, means for attaching said holder to the platen, with an end of said sheet free,

means for holding the body of the sheet ¹⁰ against the platen so that it may serve as a backing for the stencil-card, means for locking said holder to the platen to assure line-space movement therewith, and means associated with the platen for holding the ¹⁵ impression sheet against the platen adjacent the printing point.

CLARENCE M. CREWS.
